Primary Examiner — Sandra Snapp*Assistant Examiner* — Altaira J Swangin(74) *Attorney, Agent, or Firm* — Zagorin Cave LLP; Robert W. Holland(57) **CLAIM**

We claim the ornamental design for an information handling system, as shown and described.

DESCRIPTION

FIG. 1 is a front perspective view of the information handling system comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; and FIG. 7 is a bottom view thereof; FIG. 8 is a bottom perspective view thereof; FIG. 9 is a front perspective view thereof in an open position; and, FIG. 10 is a left side view thereof in an open position. Broken lines shown in the drawings illustrate portions of the information handling system and form no part of the claimed design.
